US0D1037940S

(12) **United States Design Patent** (10) **Patent No.:** **US D1,037,940 S**
(45) **Date of Patent:** **** Aug. 6, 2024**

(54) **SUSPENSION SEAT POST**

(71) Applicant: **Jiangsu Safort Metal Products Co., Ltd**, Huaian (CN)

(72) Inventor: **Shih-Chang Wei**, Huaian (CN)

(73) Assignee: **Jiangsu Safort Metal Products Co., Ltd**, Huaian (CN)

(**) Term: **15 Years**

(21) Appl. No.: **29/869,593**

(22) Filed: **Jan. 4, 2023**

(30) **Foreign Application Priority Data**

Nov. 21, 2022 (CN) 202230774721.3

(51) **LOC (14) Cl.** **12-11**

(52) **U.S. Cl.**

USPC **D12/119**

(57) **CLAIM**

The ornamental design for a suspension seat post, as shown and described.

DESCRIPTION

FIG. 1 is a rear and right side perspective view of a suspension seat post embodying my new design;
FIG. 2 is a rear and left side perspective view thereof;
FIG. 3 is a bottom, rear and right side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines depict portions of the suspension seat post and form no part of the claimed design.

1 Claim, 9 Drawing Sheets
